CLAIM

The ornamental design for a strike plate for a surgical instrument, as shown and described.

DESCRIPTION

FIG. 1 is a top perspective view of a strike plate for a surgical instrument in accordance with the new design, the bottom perspective view being a mirror image;

FIG. 2 is a top plan view of the strike plate of FIG. 1, the bottom plan view being a mirror image;

FIG. 3 is a left side view of the strike plate of FIG. 1, the right side view being a mirror image;

FIG. 4 is a front view of the strike plate of FIG. 1; and,

FIG. 5 is a rear view of the strike plate of FIG. 1.

The even-length broken lines in the figures are directed to portions of the strike plate for a surgical instrument that form no part of the claim. The dot-dash broken lines show the bounds of the claimed design and form no part thereof.
